MAGNETIC PIN DETECTION SWITCH

Donald E. Roop, Columbus, and George R. Riley, Grove City, Ohio, assignors, by mesne assignments, to Brunswick Corporation, Chicago, Ill., a corporation of Delaware

Filed Nov. 24, 1961, Ser. No. 154,555

4 Claims. (Cl. 273—52)

This invention relates to bowling pin detection means for controlling an indicating apparatus for signaling pinfall results following the rolling of a ball on a bowling alley, and more particularly relates to detection means located in the floor of a bowling alley beneath pin spots arranged in normal triangular array where pins are usually set on the alley for bowling.

It is a general object of the invention to provide a new and improved bowling pin detection means of the type described.

A more specific object is to provide a new and improved detection apparatus comprising a pin detecting switch disposed beneath a pin supporting surface including a pair of relatively movable switch contact members at least one of which carries magnetic material responsible to a magnetic field from a magnet carried by a pin on said surface for causing relative movement of the members between switch open and switch closed positions dependent upon the presence and absence of the pin.

Another object is to provide a new and improved detection means of the type described wherein the pin detecting switch is sensitive to the presence of a standing pin having a coaxial magnet in the base thereof, whether the pin is standing precisely on a predetermined spot or within a predetermined offspot area surrounding the pin spot.

It is also an object of the invention to provide a new and improved bowling pin construction wherein the pin has attached thereto adjacent the base thereof a coaxial permanent magnet having opposite ends of opposite magnetic polarity.

Other objects and advantages will become readily apparent from the following detailed description taken in connection with the accompanying drawings, in which:

FIG. 1 is a fragmentary plan view of a bowling alley embodying the principles of the present invention;

FIG. 2 is an elevational view of a panel including lamps for indicating pinfall results following the rolling of a ball on the alley; and

FIG. 3 is an enlarged fragmentary sectional view through one of the pin spots on the alley approximately at the line 3—3 of FIG. 1.

While an illustrative embodiment of the invention is shown in the drawings and will be described in detail herein, the invention is susceptible of embodiment in many different forms, and it should be understood that the present disclosure is to be considered as an exemplification of the principles of the invention and is not intended to limit the invention to the embodiment illustrated. The scope of the invention will be pointed out in the appended claims.

Referring now to the drawings in more detail, FIG. 1 illustrates the pit end of a typical bowling alley including gutters at opposite sides of the alley as at 10 and an alley proper as at 11 providing an upper surface on which pins may be set and along which a ball may be rolled at the pins. The alley may be comprised of a plurality of laminated side-by-side strips as at 12 which may be wood, though other materials may be utilized, or the alley may be made of a unitary homogenous material, the latter of which has been illustrated in FIG. 3 for purposes of simplicity. It is intended that pins would be initially set on the alley in the usual triangular pattern

2

at ten pin spots represented by solid line circles as at 14.

In many bowling establishments nowadays, automatic pinsetting machines are utilized for setting and resetting pins on the alley in proper sequence relationship to the balls thrown. During the process of a game, it is not unusual for a pin to "walk off" a pin spot after being nudged by a ball or another pin and still remain standing so that it must be lifted from the alley while the alley is swept and then reset upon the alley preferably in the offspot position assumed. Most modern day automatic pinsetter machines include pickup and resetting devices which are capable of lifting offspot pins within a predetermined range and resetting the pins in the offspot position.

A typical range of pin pickup is illustrated by the broken line circles 15 in FIG. 1 approximately three times the diameter of the pin base, though the size may vary and the shape of the offspot area may vary from circular to rectangular or some other shape, depending upon the nature of the pin pickup devices.

In some bowling alleys, the pinspots 14 as well as the offspot areas 15 may all form an integral part of a unitary construction comprised of wood laminae or of a homogenous material. In other constructions, pin spots 14 and/or the offspot areas 15, whether these define the pinsetter pickup range or not, may be defined by inserts in a construction of other material, such inserts being comprised of plastic or the like reinforced with fiber, for example, to prolong the life of the alley in the areas where pins are sometimes dropped or handled roughly when placed in position.

In any automatically operating pinfall detecting apparatus, it is highly desirable to provide for detection of offspot pins within the range of the pickup devices as well as detection of pins which remain on spot, or otherwise an inaccurate indication of pinfall results will follow. As shown in FIG. 3, a pin detecting means is provided under each pinspot for detecting standing pins either on spot or off spot within a range such as that indicated by the areas 15.

The pin detecting means at each pinspot comprises a sensing means for distinguishing between a first condition represented by a pin standing on spot or off spot within the area described surrounding the spot and a second condition represented by the total absence of any pins or by one or more fallen pins within the detection area. Since the sensing means or detecting devices at the various pinspots are all identical, only one has been illustrated in detail in FIG. 3 for purposes of simplicity, but it should be understood that there is a similar device at each of the pin spots.

Referring now to FIG. 3, each of the detecting devices comprises a pin detecting switch including a circular disc-like movable switch contact member 20 of a diameter corresponding approximately to the outer diameter of the offspot detection area 15. The movable switch contact member is adapted to cooperate with at least one, and preferably three, upright contact members as at 21 desirably terminating in pointed upper ends and angularly spaced adjacent the periphery of the member 20 at approximately 120° apart. Contact members 21 are suitably insulated and supported in any convenient manner on a base as at 22 in turn mounted as desired. As illustrated, members 21 are threaded for vertical adjustment in carriers 23 mounted on a plate 24 attached to the base 22 as by bolts or screws 25 so that upper ends of the members 21 may be readily adjusted to fall in a horizontal plane for supporting the contact member 20 in a horizontal position. The provision of three angularly spaced stationary contacts as at 21 all with pointed upper ends at once provides for support of the movable contact 20 in a horizontal plane and at the same time insures ade-

quate circuit making engagement between the stationary and movable contacts.

As will appear, it is desirable to place the switch contact members as near as practicable to the upper surface of the alley 11, and for this purpose the under side of the alley may be recessed as at 28 to receive the switch contact members at a position well above the lower surface of the alley.

To assist in maintaining the movable contact member 20 in a horizontal position and to facilitate vertical reciprocal motion of the movable contact, it carries a suitably insulated plunger 30 centrally located and extending downwardly therefrom into an upright tubular guide 31 suitably secured to the plate 24. A concentric coiled spring 32 surrounds the guide 31 and bears between the plate 24 and the disc 20, urging the latter upwardly but with insufficient force in and of itself to lift the disc 20 off the contact 21. As will appear, this provides a more sensitive operation.

The switch comprising the movable contact 20 and the stationary contacts 21 is normally closed in the absence of a standing pin on the overhead spot 14 or in the adjacent surrounding offspot area 15. It is adapted to be opened in response to the presence of a magnetic field provided by the presence of a standing pin as at 35 on the spot 14 or in the area 15. To this end, the disc contact member 20 has affixed thereto a circular disc-shaped magnet of similar diameter illustrated by reference number 36 and polarized axially so that one pole is up and the other down. In the absence of a standing pin, the magnet 36 has no effect on the operation of the switch, except of course its weight is taken into account in providing a spring as at 32 which will almost but not quite counterbalance the weight of the vertically movable parts so that the switch is normally closed but is quite sensitive and may be opened in response to the presence of a suitable attractive magnetic field provided by the presence of a standing pin as at 35 as will be described.

In order to provide the necessary magnetic field associated with the pin 35 for purposes of obtaining operation of the detecting switch, the pin is provided with a permanent magnet 38 attached to the pin base adjacent the lower end thereof. As illustrated, the magnet is cylindrically shaped and suitably secured as by adhesive means in a concentric recess in the base of the pin so that the lower end of the magnet is flush with the flat lower end of the pin. The magnet 38 is polarized axially with one pole up and the other down, in a manner such that the magnets 36 and 38 attract each other and effect operation of the switch by opening the contacts when a pin is standing on spot or offspot within the area 15. In the absence of any pin at all, or in the case of a fallen pin, the field of the magnet 38 is not effective to cause operation of the switch.

In order to make use of the detecting means described, the switch is preferably connected in circuit with a source as at 40, one side of which is connected by a wire 41 to the contact 20 and the other side of which is connected to the stationary contacts 21 as by parallel wires 42a and 42b, the stationary contacts thereby being wired in parallel so that a circuit will be made when the disc contacts any one or more of the contacts 21. As illustrated herein, the detecting means controls an indicating means in the form of a lamp 43 connected in the wire 41, so that the lamp is energized when the switch is closed in the absence of a standing pin, and the lamp is de-energized when the switch is opened in the presence of a standing pin.

The various lamps as at 43 may be arranged on a suitable indicating panel as shown in FIG. 2 at 50, the lamps being arranged on the panel in a triangular array corresponding to the arrangement of pinspots on the alley. Thus, it will be appreciated that the absence of standing pins will be indicated by an energized lamp and the presence of standing pins by a de-energized lamp.

The provision of a magnet in the pin 35 as compared to the provision merely of magnetically permeable material provides for greater field strength and more sensitive switch operation than can be provided by the provision of a magnet only in association with the switch. If a magnet is provided only in association with the switch and only permeable material is provided in the pin, the strength of the magnet in the switch must be sufficient to temporarily convert the permeable material in the pin into a magnet in order to obtain switch operation. Stronger fields and more sensitive operation with less weight are provided by use of two magnets as compared to the use of a single magnet in association with permeable material.

While the switch has been described as normally closed in the absence of a pin and opened in the presence of a pin, it will be understood that the switch could be normally open and closed by the presence of a pin. While the magnets in the switch and pin have been described as attracting each other in order to obtain switch operation, it should be understood that the magnets could be repelling in order to obtain switch operation. Although the lamps have been described as energized in the absence of a pin, it should be understood that the lamps could be de-energized in the absence of a pin and energized in the presence of a pin, and while for purposes of simplicity the readout or indication means has been illustrated as lamps, it will be understood that other means may be utilized such as a relay or more sophisticated means in the form of pin counting apparatus.

While the magnet in the pin has been illustrated as cylindrical in shape, it should be understood that it may take other forms such as, for example, a tapered shape having the larger end at the top so that the magnet is retained in place by virtue of its shape, thereby minimizing the necessity for adhesive means. In such a case, the magnet might be molded in place in a recess of conforming shape. Any of several materials may be utilized to provide the permanent magnet in the pin, including Nylon-Indox, or a combination of beryllium-ferrite and natural rubber, or Alnico V, the latter being preferable as providing the greatest strength with the least weight and mass, while the two first mentioned forms provide the advantage of being non-metallic in the strict sense of the word.

We claim:

1. In combination: a bowling pin having a coaxial magnet attached thereto adjacent the lower end thereof with opposite ends of the magnet of opposite magnetic polarity; and a detecting device, comprising, an upwardly facing surface for supporting the pin in standing position on a predetermined spot, a pin detecting switch beneath said spot including a pair of relatively movable switch contacts including a movable one which carries magnetic material responsive to the magnetic field of said pin magnet for causing relative movement of the contacts between switch open and switch closed positions dependent upon the presence and absence of said standing pin, said magnetic material being disposed throughout an area including said pin spot centrally located therein and of a size on the order of at least approximately four times the area of the pin spot thereby to detect a standing pin on said spot or anywhere within said area, and means mounting the movable switch contact for free vertical movement relative to the pin magnet without binding so that the detecting means is capable of detecting a pin when it is standing on the pin spot or anywhere within said area.

2. In a bowling pin detecting device, means providing an upwardly facing surface for supporting a bowling pin in a standing position on a predetermined pinspot corresponding in size to the base of the pin and in a predetermined area surrounding the spot, and a pin detecting switch disposed beneath said spot including relatively movable switch contact means, at least one of which in-

cludes magnetic material responsive to a magnetic field from a source above said surface at said spot for causing relative movement of the contact means between switch open and switch closed positions dependent upon the presence and absence of said field, the magnetic material being disposed throughout an area in excess of the pin base area and responsive to the presence of a field at the spot and in said predetermined offspot area surrounding the spot.

3. In a blowing pin detecting device, means providing an upwardly facing surface for supporting a bowling pin in a standing position on a predetermined spot corresponding in size to the base of the pin and in a predetermined area surrounding the spot, a pin detecting switch beneath said spot including an upwardly facing stationary switch contact member and a disc-shaped movable switch contact member reciprocable vertically relative to the stationary member between switch open and switch closed positions, gravity means urging the movable member toward the stationary member to switch closed position and a disc magnet carried by the movable member and attractable by the presence of a magnetic field from a source above said surface at said spot for causing movement of the movable member to switch open position, said movable contact member having an at-

tached plunger vertically reciprocably mounted and a coiled compression spring weaker than the gravity means surrounding the plunger in spaced relation thereto and urging the movable member upwardly toward switch open position.

4. A combination as defined in claim 3, wherein said disc magnet has a diameter substantially in excess of that of said spot for detecting the presence of a field at the spot and in said predetermined offspot area surrounding the spot.
